his Attorney

UNITED STATES PATENT OFFICE.

HUGO ADERER, OF EAST ORANGE, NEW JERSEY, ASSIGNOR TO J. F. JELENKO & CO., OF NEW YORK, N. Y., A FIRM COMPOSED OF JESSE F. JELENKO AND HUGO ADERER.

DENTAL CLASP.

Application filed April 24, 1923. Serial No. 634,365.

To all whom it may concern:

Be it known that I, HUGO ADERER, a citizen of the United States of America, residing at No. 82 South Parkway, East Orange, 5 in the county of Essex and State of New Jersey, have invented certain new and useful Improvements in Dental Clasps, of which the following is a specification.

My invention relates to the construction 10 of dental clasps.

An object of my invention is the construction of a clasp in which the connection between the anchoring member or tail-piece of the clasp and the tooth clasping member, 15 band or fingers of the clasp allows the position of the fingers to be raised or lowered without changing the position of the tail-piece, and also allows the fingers to turn on the tail-piece as a pivot.

20 A further object is the construction of a clasp which has a plurality of means for adjusting it vertically on a tooth and which also has means for relieving the stress of the band or fingers on the tooth.

25 A still further object is the construction of a clasp constituting a flexible connection between a tooth and a plate.

With these and further objects in view, one embodiment of my invention is shown 30 in the accompanying drawings, in which:—

Figure 1 is a top plan view;

Figure 2 is a side elevation;

Figure 3 is a section on line 3—3 of Figure 1;

35 Figure 4 is a section on line 4—4 of Figure 2;

Figure 5 is a perspective of a part of the tail-piece;

Figure 6 is a detail view partly in section 40 illustrating the manner in which the clasp may be used with a plate.

My clasp may be made of any suitable material such as gold clasp metal, and comprises a band 1 and a tail-piece 2. The band 45 is slit at 3 to produce fingers 4 which are duplicates. This construction of the fingers enables them to be adjusted on the tooth where desired in order to obtain a secure

hold and to prevent injury of the tooth. It will be apparent that with any suitable instrument, such as are well known to dentists, the width between the fingers may be decreased or increased. The band may have as a part thereof the usual cusp 5. One end of the tail piece may be suitably constructed 55 for the purpose of holding it firmly in the plate, as by corrugating it as shown at 6.

My novel means of connecting the band and the tail-piece will now be described and comprises a socket 7 made integral with or 60 soldered to the band 1. This socket is substantially semicircular in cross-section to receive the end 8 of the tail-piece also semicircular in cross-section, which end extends at an angle to the length of the tail-piece 65 and fits loosely in the socket to permit some turning movement of the band. The top part 8 of the tail-piece is turned down at 9 to prevent it from becoming separated from the band. When the band is raised, the end 70 of the tail-piece will fit into a notch or depression 10 in the upper edge of the socket.

In Figure 6 the clasp is shown as it may be used with a plate 11. The clasp having the anchoring member embedded in the plate 75 is attached to a natural tooth 12. Artificial teeth 13 are shown as affixed to the plate.

It will be evident that the position of the band on the tooth may be varied by moving the band up and down on the end 8 of the tail-piece. The stress or tension of the band 80 on the tooth will be relieved by means of the construction which permits pivotal movement of the band with the end of the tail-piece.

Having described my invention, what I claim is:

1. A dental clasp comprising a band and a tail-piece, a connection between said band and said tail-piece, said connection comprising a socket on said band, said socket being semicircular in cross-section and said socket having the end of the tail-piece inserted therein, said tail-piece being semicircular in cross-section. 90

2. A dental clasp comprising a band and 95

a tail-piece, and a connection between said band and said tail-piece, said connection comprising a socket on said band, said socket being semicircular in cross-section and having a notch in the upper edge thereof, and said socket having the end of the tail-piece inserted therein, said tail-piece being semi-

circular in cross-section, and said end being adapted to fit into the notch in the upper edge of said socket when the band is raised 10 on the end of said tail-piece.

In testimony whereof I affix my signature.

HUGO ADERER.
